CONVEYOR WICKET

Albert R. Philips, Brooklyn, Ohio, assignor to Young Brothers Company, Cleveland, Ohio, a corporation of Michigan

Filed Sept. 27, 1963, Ser. No. 312,245
11 Claims. (Cl. 198—134)

The present invention relates generally, as indicated, to a conveyor wicket, and, more particularly, to certain improvements in conveyor wickets of the type shown in Patent No. 2,821,286, granted to James D. Russell on January 28, 1958.

In such patent, there is disclosed a tubular wicket for supporting a lithographed or coated thin metal sheet and the like as the same is moved by a conveyor through an oven in which the printing ink or coating is baked.

Such a wicket is sufficiently strong to withstand stresses encountered during the repeated heating cycles without losing its shape and is light in construction so as to place as little a load on the conveyor as possible. The wicket also provides very little contact with the metal sheet carried thereby so that there is little interference with the flow of hot air over the sheets in the oven, thus resulting in a uniform baking of the finish.

In operation, the sheets are fed from a printing press or coating device to a position where they can be picked up by the wickets prior to entering the oven. The sheets must be properly positioned over the wickets so that when they are raised to pick up the sheets, the sheets will not slide or float thereon. If such sliding movement were allowed to occur, the sheets might assume such a position on the wickets that they would not be properly held thereby, in which case the sheets might flutter while passing through the oven, thus resulting in a nonuniform coating thereon. Or such sliding movement might so disorient the sheets on the wickets that they slide off while passing through the oven, or, at the least, result in an uneven stack when the sheets are unloaded after passing through the oven.

Once the sheets are properly oriented on the wickets, they must be securely held thereby to prevent flutter of such sheets as they pass through the oven. Further, the sheets must also be capable of being quickly and easily removed from the wickets subsequent to the baking operation.

The conveyor is generally provided with a great many wickets secured thereto in closely spaced relation with respect to each other. The wickets must be disposed at a slight rearward inclination relative to the direction of movement of such conveyor so that the uncoated faces of the sheets rest against the front faces of the wickets.

It is therefore a primary object of this invention to provide an improved wicket construction which will allow the sheets to be conveyed to a position where they can be picked up by the wickets with a minimum of relative sliding movement.

It is another object of this invention to provide such wickets with a novel holding means for securing the sheets against the wickets to prevent sheet flutter and to release the sheets quickly and easily when desired.

An additional object is to provide a novel means for properly spacing the wickets on the conveyor.

It is another object to provide a rest bar having integral sheet support clips thereon.

It is another object to provide a conveyor wicket with novel sheet support clips for supporting a wide range of sheet sizes.

Other objects and advantages of the present invention will become apparent as the following description proceeds.

To the accomplishment of the foregoing and related

2

ends, the invention, then, comprises the features herein-after fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

FIG. 1 is a front elevation of one form of my improved wicket construction in accordance with the present invention;

FIG. 2 is a side elevation of such wicket;

FIG. 3 is an enlarged sectional view taken on the plane of the line 3—3 in FIG. 1;

FIG. 4 is an enlarged detail horizontal section taken on the plane of line 4—4 of FIG. 1 showing the improved rest clip construction;

FIG. 5 is a vertical sectional view taken on the plane of the line 5—5 in FIG. 4;

FIG. 6 is a fragmentary front elevation of a portion of a wicket frame illustrating a further modification of the rest clip; and

FIG. 7 is an enlarged vertical sectional view taken on the plane of the line 7—7 in FIG. 6.

Referring now to the drawings in detail, I have illustrated in FIG. 1 one form of my improved wicket construction which comprises a tubular frame 1 having a generally rectangular configuration with two slots 2 and 3 in the outer edge thereof. The slots preferably extend approximately three-fourths of the length of the wicket frame and are so dimensioned that the belts of a conveyor (not shown) can be positioned to extend into the same. Thus when metal sheets are fed to a position adjacent the wickets from a printing press or coating device, they can be picked up by oven feed conveyor belts and accurately conveyed to such a position over the wickets that when the wickets are raised to pick up the sheets, there will be a minimum of sliding or floating movement therebetween.

The elimination of all such sliding movement is desirable since it can cause misalignment of the sheets on the wickets to such an extent that they cannot be firmly gripped by the wickets. Consequently, as the conveyor passes through the oven, the conveyor pulsation, air flow, etc. may cause the sheets either to fall off the wickets or flutter, thus resulting in uneven or marred coatings thereon. Moreover, when the sheets are automatically unloaded after having passed through the oven, they will not stack evenly.

The frame 1 is comprised of three generally inverted U-shape members 4, 5, and 6 interconnected by U-shape braces 7 and 8, which define the depth of the slots 2 and 3, respectively.

Within the members 4 and 6 are provided braces 9 and 10, respectively, the lower ends of which are secured to the outer legs 11 and 12 as by brazing. The braces 9 and 10 extend upwardly from the outer legs 11 and 12, respectively, in a convergent direction until they engage the inner legs 13 and 14 of the members 4 and 6 and then in a divergent direction until they again engage outer legs 11 and 12, respectively, and are secured to such legs at their points of engagement by brazing.

Also within the members 4 and 6 are lower braces 15 and 16, the upper ends of which are secured to the inner legs 13 and 14, respectively. These lower braces 15 and 16 extend downwardly in a divergent direction until they engage the lower ends of braces 9 and 10, respectively, and then extend downwardly parallel with the outer legs 11 and 12, and are secured to braces 9 and 10 at their respective points of engagement.

Within the inverted U-shape member 5 there are dis-

posed two braces 17 and 18 having outer ends 19 and 20 oppositely directed and brazed in laterally spaced relation to each other to the bight portion 21. The braces 17 and 18 extend downwardly in a convergent direction until they come into contact with each other and then extend horizontally in opposite directions until they bend upwardly and engage the legs 22 and 23, respectively, these points of engagement also being secured by brazing and horizontally aligned with the tops of braces 15, 7, 8, and 16.

The ends of the legs of the inverted U-shape members and the lower ends of the lower braces 15 and 16 are secured to a lower rest bar 24. The rest bar is shown in FIG. 5 as a solid thin metal bar having a generally rounded and flanged cross-section. However, the bar can also be made of perforated metal, expanded metal, screen, etc. to permit the unobstructed passage of air therethrough while in the furnace so that the finish on the sheets can be uniformly baked. Such perforations can be of any one of a number of shapes, such as rounded, diagonal, rectangular, diamond, or triangular. Moreover, if desired the bar may have a rectangular cross-section to increase the stiffness thereof.

Projecting outwardly from the rest bar 24 are end rest clips 25 and intermediate rest clips 26. Preferably, the rest clips are formed integral with the rest bar, thus giving a simple one-piece construction which eliminates the need for having accurately to position prefabricated clips on the bar and weld them thereto. However, it should be understood that the clips can be made separately from the rest bar and welded thereto if desired.

As can readily be seen in FIGS. 4 and 5, each of the intermediate rest clips 26 includes an outwardly extending base portion 27 having a hole 28 through which the end of one of the inner legs 13 and 14 of the inverted U-shape members 4 and 6 or the end of one of the legs 22 and 23 of the inverted U-shape member 5 extends, and an upwardly and outwardly extending arm portion 29. At the junction of the base member 27 and arm 29 there are provided two laterally spaced inwardly extending projections or indentations 30, the spacing therebetween being such that one of the projections is disposed on either side of the leg of the inverted U-shape member extending through the hole 28 in the base 27 as viewed in FIG. 1.

Each end rest clip 25 has a configuration similar to that of the intermediate rest clips 26 except that it is longer than the intermediate clips so as to embrace the end of one of the outer legs 11 and 12 of the inverted U-shape members 4 and 6 and the lower end of one of the lower braces 15 and 16, and it has only one inwardly extending projection 30 at the junction of the base member 27 and arm 29, such projection being disposed adjacent the inward side of the lower end of one of the lower braces 15 and 16 as viewed in FIG. 1.

Anchor pins 31 are positioned between the ends of the outer leg 11 and the lower brace 15 and between the ends of the outer leg 12 and the lower brace 16, and extend downwardly through the hole 28 in the end clips 25. The lower ends of these pins are adapted to be attached to links of an endless conveyor chain (not shown) which is adapted to move through an oven of the type disclosed in the previously mentioned Russell Patent No. 2,821,286. A more detailed disclosure of such an oven may be found in Patent No. 2,406,821, granted to V. A. Fox on September 3, 1946.

The configuration of the rest clips not only permit them to aid in the placement of a metal sheet on each of the wickets, but also to hold securely the sheets to the wickets to prevent them from fluttering as they are conveyed through the oven. Further, the sheets can be removed quickly and easily from the clips when desired.

Thus, when the sheets are fed to the desired position over their respective wickets, the leading edge thereof will come into engagement with the outer ends of the arms 29 of the clips 25 and 26 so that when the wickets

are raised to pick up the sheets, such leading edge will slide downwardly along the inner surfaces of the arms 29 until it comes to rest on the base 27 of the clips, the sheets being so disposed that the uncoated surface thereof is facing the tubular frame of the wickets. When in this position the edge of the sheets S will be slightly bowed around each of the ends of the legs of the inverted U-shape members in the manner shown in FIGS. 4 and 5 due to the relative disposition of the projections 30 on the clips 25 and 26 with respect to such legs. The metal sheets, being thin and quite flexible, will assume the bowed configuration due to the force of gravity acting thereon and thus effect a tight engagement with the wickets. Moreover, since the sheets are merely flexed or bowed, rather than wedged into tight engagement with the wickets, they can be easily removed from the wickets after the backing operation by a withdrawal conveyor having belts disposed in the slots of the wickets.

Top spacer clips 32 are securely fastened to the bight portions of each of the U-shape members 4, 5, and 6. As can be seen in FIG. 3, the spacer clips 32 include a base portion 33 having a downwardly projecting flange 34 extending from the outer end thereof and a hook-shape member 35 extending downwardly from the inner end, such hook-shape member being formed to fit the tubular sectional configuration of the bight portion. When so formed, greater accuracy in positioning the clips 32 on the frame can be achieved. Thus, when a plurality of such wickets are secured to a conveyor they will be maintained in closely spaced relation by the clips 32 and also be disposed at a slight rearward inclination relative to the direction of movement of the conveyor to allow the uncoated faces of the sheets to rest against the unobstructed front faces of the wickets.

A further refinement of the conveyor wicket is shown in FIG. 6, wherein extra long end rest clips 36 have been substituted for the end rest clips 25 and the intermediate rest clips 26 may be eliminated. These long rest clips 36 have particular utility when it is desired to use the same wicket to support sheets of different sizes since the ends of the leading edge of the sheets can be properly supported by such rest clips within a broad range of sizes. Moreover, such long rest clips 36 can give the proper support to a sheet having a scrolled, notched, or other irregularly shaped leading edge, while shorter rest clips will not be able to provide the desired support if the highs and lows of the leading edge of the sheets have a length greater than the length of the rest clips.

The arms 29 of the rest clips 36 may be provided with perforations 37, if desired, to permit unobstructed passage of the air in the oven, thus insuring more uniform heating of the sheets. In addition, perforations 37 may also be provided in the base member 27 of the rest clips 36, as clearly shown in FIG. 7.

Other modes of applying the principles of the invention may be employed, change being made as regards the details described, provided the features stated in any of the following claims or the equivalent of such be employed.

I therefore, particularly point out and distinctly claim as my invention:

1. A conveyor wicket comprising a tubular frame, said tubular frame including a plurality of spaced apart leg members, a rigid rest bar extending across the lower ends of said leg members, a plurality of rest clips extending upwardly and outwardly from one side of said rest bar, one said clip being located adjacent each leg member, said rest clips having at least one inwardly extending projection therein disposed on one side of said leg members, said projections being adapted securely to hold a thin metal sheet against said tubular frame.

2. The conveyor wicket of claim 1 wherein the rest clips adjacent the outermost leg members have only one inwardly extending projection therein and the intermediate rest clips have two inwardly extending projections, one

being disposed on either side of the respective leg members.

3. The conveyor wicket of claim 1 wherein said rest clips and rest bar are of a one-piece construction.

4. A conveyor wicket comprising a tubular frame, a rigid rest bar secured to the lower end of said tubular frame, a plurality of upwardly and outwardly extending rest clips secured to one side of said rest bar, and a plurality of inwardly extending projections on said rest clips, said projections being adapted securely to hold a thin metal sheet against said tubular frame.

5. The conveyor wicket of claim 4 wherein only two rest clips are secured to said rest bar, said rest clips being sufficiently long to support metal sheets of different sizes.

6. The conveyor wicket of claim 4 wherein said rest clips are extra long, thus being adapted properly to support metal sheets having irregularly shaped leading edges.

7. The conveyor wicket of claim 6 wherein said rest clips are provided with a plurality of perforations to permit the unobstructed passage of air as said wicket is conveyed through an oven.

8. A wicket for use in a sheet conveyor comprising a tubular frame having a generally rectangular configuration with a plurality of belt receiving slots in the upper edge thereof, a rigid rest bar secured to the lower end of said tubular frame, a plurality of upwardly and outwardly extending rest clips secured to one side of said rest bar, a plurality of inwardly extending projections on said rest clips, said projection being adapted securely to hold a thin metal sheet against said tubular frame, and a plurality of top spacer clips securely fastened to said tubular frame, each of said spacer clips including a hook-shape portion extending downwardly from one end thereof, said hook-shape portion being formed to fit the tubular configuration of said frame.

9. The wicket of claim 8 wherein said rest clips and rest bar are of a one-piece construction.

10. The conveyor wicket of claim 8 wherein said tubular frame includes three inverted U-shape members

laterally spaced from each other and disposed in the same plane, said inverted U-shape members being connected together by braces secured to their adjacent leg members, said braces defining the bottom of said belt receiving slots.

- 5 11. A conveyor wicket comprising a tubular frame having a generally rectangular configuration, said tubular frame including a plurality of laterally spaced inverted U-shape members secured together by braces joining the adjacent legs thereof, said braces and adjacent legs defining belt receiving slots in said tubular frame, support braces disposed within said inverted U-shape members, a rigid rest bar secured to the lower ends of said inverted U-shape members, a plurality of rest clips extending upwardly and outwardly from one side of said rest bar, said rest bar and rest clips being of one-piece construction, one of said rest clips being disposed adjacent each leg of said inverted U-shape members, said legs extending through an aperture in said rest clips, a plurality of inwardly extending projections on said rest clips, said projections being adapted to retain a thin metal sheet in position against said tubular frame, and a spacer clip secured to the bight portion of each of said inverted U-shape members, said spacer clips being formed to fit the tubing of said frame to provide greater accuracy in positioning said rest clips thereon.
